UNITED STATES PATENT OFFICE.

WILLIAM E. JACOBS, OF COLUMBUS, OHIO.

ROAD-SCRAPER.

SPECIFICATION forming part of Letters Patent No. 325,934, dated September 8, 1885.

Application filed June 26, 1885. (No model.)

To all whom it may concern:

Be it known that I, WILLIAM E. JACOBS, a citizen of the United States, residing at Columbus, in the county of Franklin and State 5 of Ohio, have invented certain new and useful Improvements in Wheeled Road Scrapers or Excavators; and I do hereby declare the following to be a full, clear, and exact description of the invention, such as will enable others skilled in the art to which it appertains to make and use the same.

My invention consists in a scraper comprising wheels, a crank-axle, hangers, lever-frame, latching device, tongue and bail, and connecting-links between the lever-frame and crank-axle, the said parts being constructed, arranged, and combined in a novel and useful manner, as will be hereinafter described and claimed.

The leading object of my invention is to 20 easily raise the bowl. This I accomplish by forcing back the lever-frame, and thereby holding the wheels back while the team is pulling the bowl forward, so as to turn the cranked portion of the axle forward, causing it to raise 25 the bowl.

In the accompanying drawings, Figure 1 is a side elevation of the scraper as in operation of gathering a load; Fig. 2, a similar elevation as it appears raised and transporting 30 its load; Fig. 3, a similar elevation as it appears in the act of dumping its load; and Fig. 4 is a front elevation of the scraper as shown in Fig. 1.

A in the accompanying drawings represents 35 the bowl of the scraper, provided with handles *a*, stop-catch *a'*, and side hangers, *A'*, extending up from its sides above the top of the bowl.

B is a cranked axle hung loosely in the hangers *A'*, and having on the journal ends *b* of its 40 cranked arms *b'* wheels *C*, which revolve freely.

D *D'* designate the lever-frame, provided with a sliding spring-acted latch-bolt, *d*, and E *E'* designate the bail and tongue.

The front ends of the lever-frame and the 45 rear ends of the bail *E* of tongue *E'* are pivoted to the sides of the bowl, near the front and bottom thereof, by bolts *e*, on which the lever-frame D *D'* and bail and tongue E *E'* have vibratory movements in common.

50 The crank-arms *b'* of the axle are coupled to the lever-frame by links *FF*, pivoted by bolts to said frame, and fitted by eyes upon the jour-

nal ends *b* of said axle, and having free movements thereon, as well as on the pivot-bolts *f*, by which they are connected to the lever-frame. 55

From the foregoing description and accompanying drawings it will be seen that by the arrangement, as shown, of the lever-frame D *D'*, and its connection by the links *FF* with the journal ends *b* of the cranked axle B, a great 60 purchase is secured when starting to lift the loaded scraper from the position shown in Fig. 1 to the position shown in Fig. 2, and that this purchase or leverage continues to increase until the bowl is raised to its highest point—say 65 about eight inches above the ground—and the nearer the bowl gets to its highest point the greater will be the assistance of the team, pulling against the cranked part of the axle, in raising the load.

In operating with this scraper the lever-frame D *D'* is unlatched from the condition shown in Fig. 2, and the parts adjusted as in Fig. 1, which is the condition for gathering a load. To lift the scraper-bowl to the position 75 shown in Fig. 2 the operator holds back the wheels C *C* by pulling back upon the lever-frame while the team is pulling forward upon the bowl A and the cranked axle B. This combined action of the team and operator insures the elevation of the bowl, and nearly the whole labor is performed by the team. This is due to the wheels taking a fair hold upon the ground and the axle turning in the wheels, while its cranked arms are turned forward 80 from a nearly horizontal to a vertical position and latched by the devices *a'* *d*. When the load is to be dumped, the operator turns the bowl from the position shown in Fig. 1 to that shown in Fig. 3, or to any other position usual 85 in dumping wheeled scrapers, and, if necessary, causes the team to move the scraper forward or backward.

I am aware that there are a number of patented wheeled scrapers somewhat resembling 95 in general construction mine, some of which work much easier than others. Those in which the wheels are pulled or held back while lifting the load, operate much the easiest; also, those having the hangers rigid to the bowl rise 100 easier, because the team helps to raise by pulling forward the cranked part of the axle. I find that by pivoting the lever-frame, with the bail of the tongue, to the forward lower part

of the bowl and connecting the lever-frame to the axle-arm by the links F F, I secure increased power over any other plan of like simplicity and strength as mine, as the team, by pulling the scraper while lifting the load, is really made to lift the bowl—that is, when the lever-frame is operated by hand and the wheels are held back, which is easily done, especially if the wheels are made small and the ground upon which they are made to travel while filling and lifting is rough enough to give them a proper hold or frictional contact.

During the operations of the scraper its attached tongue at its forward end is prevented from descending too low by stop pins a^3 , and the hangers A' are kept from moving too far forward by the stop-pins a^2 , as will be understood from the drawings. While the pins a^3 operate as described, they do not prevent the bowl from moving down from the position shown in Fig. 2 to the position shown in Fig.

1; nor do the pins a^2 interfere with the forward movement of the crank-arms of the axle.

What I claim as my invention is—

1. A road scraper or excavator comprising a cranked axle, wheels, a bowl, hangers, a bail and tongue, a lever-frame, a latching device, and links connecting the lever-frame with the cranked axle, said parts being constructed, combined, and operating substantially as and for the purpose described.

2. The combination of the lever-frame D D', pivoted to the bowl at e, forward of and below the axle, the hangers A', the bowl A, the crank-axle B, passed through the upper portion of the hangers and having wheels on its arms, the links F, connected directly to the arms of the axle and to the lever-frame at points in rear of the axle, a tongue suitably connected to the bowl, and stop-pins a^2 a^3 , substantially as and for the purpose described.

In testimony whereof I affix my signature in presence of two witnesses.

WILLIAM E. JACOBS.
